UNITED STATES PATENT OFFICE.

DAVID WARRING, OF BOSTON, MASSACHUSETTS.

IMPROVEMENT IN LADIES' HEAD-COMBS.

Specification forming part of Letters Patent No. 129,441, dated July 16, 1872.

To all to whom these presents shall come:

Be it known that I, DAVID WARRING, of Boston, in the county of Suffolk and State of Massachusetts, have made an invention of a new and useful as well as attractive Ladies' Head-Comb; and do hereby declare the following to be a full, clear, and exact description thereof, due reference being had to the accompanying drawing making part of this specification, and in which—

Figure 1 is a perspective view of my invention in an expanded state, Fig. 2 being a vertical section, and Fig. 3 an outer face view of the same in a closed or contracted state.

The invention herein described is an attachment to a lady's "tuck or twist" comb; and it consists in combining one or more imitation or artificial leaves or other articles of ornament with the comb by means of an intervening spring, in such manner that when the comb is passed into the back hair the ornament shall partially overlap and cling to the chignon or head-dress, while the leaves are applied to the spring in such manner that, as before stated, they may, if desirable, be expanded into a cluster, the spring itself being attached rigidly to the comb.

The drawing accompanying this specification represents at A a lady's tuck-comb of ordinary form. B represents a plate spring, bent into the form of a yoke, one arm, a, of which is securely and rigidly attached to the inside of an imitation or artificial leaf, c, which depends from it, while the other end or arm is attached to the comb, as shown. In addition to the leaf c, attached to the spring B, I apply thereto one or more additional leaves, d,

of a size and form corresponding substantially with the leaf c, behind which they are disposed, the aggregate leaves being disposed one behind the other when unexpanded; as shown in Fig. 3 of the drawing. The leaves are all disposed preferably with their stems upward, and all but the middle one are pivoted at or near their stem to the stem B, in order that they may be spread or expanded into a cluster, as shown in Fig. 1, which produces a very pleasing effect. The leaves may be composed of thin metal, struck up in a suitable die, or they may be produced from horn, or tortoise, or other substances, as I do not confine myself to any given material.

When applied to use the comb is passed into the back hair in the usual manner, and the leaves allowed to overlap and press upon the chignon, chatelaine or Grecian braid, or other head-dress of hair or other material, the spring serving not only to retain the ornament in place, but the chignon also to a certain degree.

Having thus described my invention, what I claim, and desire to secure by Letters Patent, is—

As a new manufacture, a lady's comb provided with one or more artificial leaves or other articles of ornament, connected with it by a spring, substantially in the manner described, whether one or more of said leaves or other articles are pivoted to the spring or not.

DAVID WARRING.
